UNITED STATES PATENT OFFICE.

HENRY O'NEILL, OF GREENSBURG, PENNSYLVANIA.

FLASK.

Application filed September 10, 1921. Serial No. 499,810.

To all whom it may concern:

Be it known that I, HENRY O'NEILL, a citizen of the United States, residing at Greensburg, in the county of Westmoreland and State of Pennsylvania, have invented certain new and useful Improvements in Flasks, of which the following is a specification, reference being had to the accompanying drawings.

10 This invention relates to certain improvements in flasks and has relation more particularly to a device of this general character especially designed and adapted for use in or around mines or other places where carbide and water are used for illuminating purposes, and it is an object of the invention to provide a novel and improved device of this general character comprising two containers, one for water and the other 15 for carbide.

Another object of the invention is to provide a novel and improved device of this general character which is adapted to be supported from a belt or other wearing apparel and wherein the flask proper is supported for swinging movement to facilitate the discharge of the contents from within the flask.

The invention consists in the details of 20 construction and in the combination and arrangement of the several parts of my improved flask whereby certain important advantages are attained and the device rendered simpler, less expensive and otherwise 25 more convenient and advantageous for use, as will be hereinafter more fully set forth.

The novel features of my invention will hereinafter be definitely claimed.

In order that my invention may be the 20 better understood, I will now proceed to describe the same with reference to the accompanying drawings, wherein:

Figure 1 is an elevational view of a flask constructed in accordance with an embodiment of my invention;

Figure 2 is a view partly in vertical section and partly in side elevation of the device as illustrated in Figure 1;

Figure 3 is a view in rear elevation of the 50 device as herein disclosed; and

Figure 4 is a view in top plan of the flask as herein embodied.

As disclosed in the accompanying drawings, S denotes a support embodying an 55 elongated member or strap 1 terminating at one end in a rearwardly facing hook 2

adapted to be engaged with a belt or other wearing apparel so that the device in its entirety may be conveniently carried by a person.

The opposite or lower end portion of the member or strap 1 is provided with a loop member 3 of desired dimensions and configuration and which extends substantially at right angles from the strap or member 1 60 65 and outwardly therefrom.

The flask F comprises two containers 4 preferably cylindrical in form and connected one to the other, said connecting means including a rear plate 5 of a length 70 substantially co-extensive with the lengths of the containers 4.

One of the containers 4 is adapted to contain a supply of water and an end thereof is provided with a comparatively small 75 screw cap or top 6. The second container 4 is adapted to carry a supply of carbide and the opposite end thereof, or the end remote from the screw cap 6, is provided with a relatively large screw cap or top 7 to facilitate either the filling of the associated container or discharging the carbide therefrom.

The plate 5 is provided longitudinally thereof with a slot 8 through which extends 85 a bolt 9 or the like carried by the member or strap 1 and engaged with the outer extremity of the bolt 9 and inwardly of the plate 5 is a holding member 10 whereby the flask F is held to the support S.

Normally, the flask F extends through the loop member 3 and substantially snugly engages therein so that the flask F is held against swinging movement about the bolt 9 or the like. When either water or carbide 95 is needed for a lamp, the flask F is raised upwardly as will be permitted by the slot 8 and said flask is turned in the requisite direction so that either the water container or the carbide container will be in the right 100 position to feed into a lamp.

From the foregoing description it is thought to be obvious that a flask constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting

myself to the precise arrangement and formation of the several parts herein shown in carrying out my invention in practice except as hereinafter claimed.

5. I claim:

1. A device of the character described comprising, in combination, a loop member, supporting means therefor, and a flask slidably and rotatably attached to the supporting means and normally extending through the loop member.

15. 2. A device of the character described comprising, in combination, a loop member, supporting means therefor, and a flask slidably engaged with the supporting means and normally extending through the loop member, said flask comprising two containers, an end portion of one of the containers being provided with a discharging means and the 20 opposite end portion of the second container being provided with a discharging means.

20. 3. A device of the character described comprising, in combination, a supporting

member, a flask, a plate carried by the flask provided with a slot, attaching means carried by the member and extending through the slot of the plate whereby the flask is capable of swinging movement and endwise movement relative to the supporting member, and means carried by the supporting 30 member for normally holding the flask against swinging movement.

4. A device of the character described comprising in combination a supporting means, a flask rotatably engaged with the 35 supporting means, said flask comprising two containers, an end portion of one of the containers being provided with a discharge means, the opposite end portion of the second container being provided with a discharge 40 means, and means for normally holding the flask against turning movement.

In testimony whereof I hereunto affix my signature.

HENRY O'NEILL.
